UNITED STATES PATENT OFFICE.

JACOB H. BECKMAN, OF SEATTLE, WASHINGTON.

CAR-REPAIRING DEVICE.

1,266,093.

Specification of Letters Patent. Patented May 14, 1918.

Application filed June 4, 1917. Serial No. 172,838.

To all whom it may concern:

Be it known that I, JACOB H. BECKMAN, a citizen of the United States, and resident of the city of Seattle, county of King, and 5 State of Washington, have invented certain new and useful Improvements in Car-Repairing Devices, of which the following is a specification.

My invention relates to devices intended 10 for handling automobiles, auto trucks, and similar vehicles, to place them in position such that operations of repair, inspection, et cetera, may be more conveniently conducted. The major part of the repair work upon 15 automobiles has to do with the power plant mechanism and transmission, considerable of which is beneath the body of the car, and is not readily accessible.

The object of my invention is to provide 20 a convenient means for placing the car on one side and holding it in this position for such repair work.

My invention comprises the novel constructions and combinations of parts which 25 will be first described and then particularly pointed out in the claims.

In the accompanying drawings I have shown my device embodied in the types of construction which are now most preferred 30 by me.

Figure 1 is a plan view of my device in normal position.

Fig. 2 is an end elevation of the parts in the same position.

Fig. 3 is an end elevation of the device 35 after it has been turned so as to place the car upon its side.

Fig. 4 is a detail showing the manner of connecting up certain of the parts which are 40 carried by the pivot shaft.

Figs. 5 and 6 are two views showing, from different directions, the manner of connecting the supporting bars at the side and for supporting the side of the car.

Figs. 7 and 8 are two views showing the manner of lashing the wheels of the car to their support.

The central idea of this invention is to provide a mechanism which may have engaging supports under the car wheels, together with supports for one side of the car after it has been turned up, whereby the car may be secured thereto and then turned up on its side so as to make the portion of the car

which is under the body, readily accessible. 55 To this end I have employed a pivot shaft 1 as the basis from which to operate.

This pivot shaft is mounted in suitable bearings extending parallel to the position to be occupied by the car. Secured to this 60 shaft are beams 2 which extend laterally at each side of the shaft. One end of these beams is of sufficient length to extend entirely under a car which is placed thereover. The other end of the beam extends at the 65 opposite side of the shaft and is provided with a counter weight 22, whereby the weight of the car may be counter balanced to such an extent as is found desirable.

The manner of securing these beams 2 in 70 place is illustrated in Fig. 4. A casting has a hub 10 which is keyed or otherwise secured to the shaft. It also has a web 11 provided at its edges with flanges 12, which are of such a length, in a direction transversely of the 75 shaft, as to furnish a liberal bearing for the beam 2. The beam 2, as herein illustrated, is shown as a channel.

I have shown three of these beams 2, one positioned so as to correspond with, and intended to support, the forward wheels of an 80 automobile. The other beams are spaced apart a sufficient distance so that the longitudinal angle bars 15, which are secured thereto and form the immediate support for 85 the wheels of the car, are of such length as to accommodate the rear wheels of cars of different length of wheel base. These wheel-supporting members are preferably made no longer than necessary, to thereby obviate 90 their interference with work upon the car after it is turned up. The central section 19 is not mounted on the beams 2.

The inner of the beams 15, that is, the one which is nearest the shaft 1, is fixedly secured to the beams 2. The outer beam 15, or that which supports the wheels farthest removed from the shaft 1, are preferably made adjustable toward and from the shaft within certain limit, whereby, because of such an 100 adjustment, automobiles of different treads may be accommodated. While most automobiles are of standard treads, some are of a broader or a narrower gage than others, and this adjustment will permit accommo- 105 dating such cars.

The manner of securing this adjustment is clearly shown in Fig. 7. The angle bar

15, which supports the wheel, has a bracket 16 secured to the under side thereof in position to engage a side surface of the channel 2. It also has bracket 17 secured to its vertical side and this has a bolt 18 passing through the same, the lower end of which is bent laterally to project under the flange of the channel 2. By this means, the outer angle bar 15, which supports the car wheels, 10 may be adjusted for any position along the channel bar 2.

Means should be provided whereby the wheels may be lashed to the member by which they are supported, so that, when the 15 car is placed on its edge it will be held securely. A convenient means for doing this has been illustrated and consists in securing plates or bars 13 to both the top and bottom webs of the angle bar, these plates having 20 side projections 14 about which ends a lashing rope 21 may be placed.

At a point approximately adjacent the location of the pivot shaft 1, vertical posts are 25 secured to the beams 2, these extending upward to a height approximately equal to that of the body of the car. These posts 20, as herein shown, are also made of channel bars. Means are provided whereby the 30 weight of the car, when it is turned on its side, may be largely supported from these beams. These means may be varied in construction. The means shown consist of providing horizontally extending beams 3, which are also shown as channel bars, and providing 35 means whereby these beams may be clamped at any height desired to the posts 20, and in further providing means movable lengthwise of the horizontal beams 3 which may be adjusted toward and from the car 40 and act as the direct support for the car.

The means illustrated for securing the horizontal bars 3 to the vertical posts 20 consists of employing U-bolts 30, which embrace both the posts 20 and the horizontal bars 3, 45 these U-bolts passing through a bar 31 and clamping the posts and the horizontal bars 3 together.

The means for supporting the car from these beams 3, as herein shown, consists in 50 providing blocks 4 which fit within the channel sides of the two bars 3 so as to be held thereby and to permit of adjustment.

In order to do this the two bars 3, which are associated together, are placed with their 55 flanges projecting, each toward the other. The block 4 is threaded and has a threaded bar 40 secured therein. One end of this bar is provided with a wheel 41, or with any other mechanism by which it may readily be 60 turned. The other end is provided with a block or plate 42, which preferably has a ball and socket, and rotative connection therewith, whereby, when it engages the side of the car, it may rock to such an angle as 65 may be necessary to fit the side of the car and

will not turn as the supporting bar 40 is turned.

The horizontal bars 3, which are arranged in pairs, and of which preferably two pairs are employed, one, in connection with the 70 lower part of the car, that is with the chassis, and the other of which is employed in connection with the upper or body part of the car, being freely and universally adjustable vertically, may be adjusted to fit any condition. In fact, this adjustment may be of such a nature that the car is placed on an incline from one end to the other. The blocks 4, which contain the screw threaded bars 40, are adjustable lengthwise of the 75 bars, 3, so as to fit any portion of the car needed. As a consequence, the car may be supported from any point desired.

Means which I prefer to use in turning the car on its edge, consists of a segment 85 wheel 5 which is secured to the shaft 1 and which forms a segment of a worm gear. Meshing with this is a worm 50 which may be turned by any means desired. The shaft of this worm may be provided with means 90 for turning by hand or, as has been illustrated, it may be provided with means for turning by power. These means, as shown, consist of bevel gears 51 which connect the shaft of the worm and the shaft 52 of an 95 electric motor 53. Any other suitable means of applying the power might be employed.

It is evident that with this device a car may be placed on its side so as to make any operating mechanism readily accessible for 100 any desired purpose.

To further secure the car body when turned upon its side, I may employ belts, ropes or equivalent means 6, secured to the car body and to the trackway members, 15, 105 as is indicated in Figs. 2 and 3.

What I claim as my invention is:

1. An apparatus for upturning and holding automobiles in repairing, comprising two sets of supporting arms at substantially 110 right angles, pivotal supports for said arms adjacent the angle of joining, means for clamping the automobile to those arms which normally are horizontal, and supporting means carried by the other arms and adjustable relative thereto both vertically and 115 horizontally and adapted to engage the side of the automobile.

2. An apparatus for upturning and holding automobiles in repairing, comprising 120 two sets of supporting arms at substantially right angles, pivotal supports for said arms adjacent the angle of joining, means for clamping the automobile to those arms which normally are horizontal, and supporting means for the side of the automobile comprising threaded bars having bearing blocks 125 adapted to engage the sides of the automobile, complementary threaded blocks receiving said bars and horizontal bars vertically ad- 130

justable on the vertical supporting arms, and means for adjusting the threaded blocks on the horizontal bars.

3. An apparatus for upturning and holding automobiles, comprising a pivot shaft, horizontal bars fixed to said shaft and adapted to extend under respectively the front and rear wheels of an automobile, means for securing the automobile to these horizontal

bars, vertical bars extending upward from the pivot shaft, and thrust bars supported from and universally adjustable upon the vertical bars and adapted to engage side surfaces of the automobile.

Signed at Seattle, Washington, this 28th 15 day of May, 1917.

JACOB H. BECKMAN.
